(57) **CLAIM**

The ornamental design for a headband bracket for a headset for telephone and communication equipment, as shown and described.

DESCRIPTION

FIG. 1 is a front view of a headband bracket for a headset for telephone and communication equipment showing the new design.

FIG. 2 is bottom plan view of FIG. 1 thereof.

FIG. 3 is a top plan view of FIG. 1 thereof.

FIG. 4 is a right side plan view of FIG. 1 thereof.

FIG. 5 is a left side plan view of FIG. 1 thereof.

FIG. 6 is a rear plan view of FIG. 1 thereof.

FIG. 7 is a front perspective view of FIG. 1 thereof.

FIG. 8 is a front view of a second embodiment of a headband bracket for a headset for telephone and communication equipment showing the new design.

FIG. 9 is bottom plan view of FIG. 8 thereof.

FIG. 10 is a top plan view of FIG. 8 thereof.

FIG. 11 is a right side plan view of FIG. 8 thereof.

FIG. 12 is a left side plan view of FIG. 8 thereof.

FIG. 13 is a rear plan view of FIG. 8 thereof; and,

FIG. 14 is a front perspective view of FIG. 8 thereof.

The features shown in broken lines depict environmental subject matter only and form no part of the claimed design.
